(57) **CLAIM**

The ornamental design for a compact disc holder, as shown and described.

DESCRIPTION

FIG. 1 is a front elevational view of a compact disk holder showing my design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines showing a CD case throughout the views, represent the environment in which the design resides; and they from no part of the claim.
